UNITED STATES PATENT OFFICE.

JAMES S. PATTEN, OF BALTIMORE, MARYLAND.

DESIGN FOR A DUST-GUARD SECTION.

SPECIFICATION forming part of Design No. 29,768, dated December 6, 1898.

Application filed November 12, 1898. Serial No. 696,312. Term of patent 14 years.

To all whom it may concern:

Be it known that I, JAMES S. PATTEN, a citizen of the United States, residing at Baltimore, in the State of Maryland, have invented and produced a new and original Design for Dust-Guard Sections, of which the following is a specification, reference being had to the accompanying drawings, forming part thereof, in which—

Figure 1 is a perspective view of a dust-guard section, showing my new design; and Fig. 2 is a cross-sectional view on about line 22 of Fig. 1.

As shown in the drawings, the leading or material feature of my design consists of the plate having the curved edge A and the inwardly-sloping grooves B in the opposite side

edges. A minor feature is the groove C, extending from side to side of the plate at its upper edge and opening into the grooves B at 20 the base of same.

The grooves B and the curved edge A unite in producing a bifurcated effect at both sides of the plate, at one end thereof.

Having described my invention, what I 25 claim as new, and desire to secure by Letters Patent, is—

The design for a dust-guard section, as herein shown and described.

JAMES S. PATTEN.
